Attorney

UNITED STATES PATENT OFFICE.

GRIFFITH E. WILLIAMS, OF CAMBRIA, WISCONSIN.

BOMB.

1,300,537.

Specification of Letters Patent. Patented Apr. 15, 1919.

Application filed October 14, 1918. Serial No. 257,988.

To all whom it may concern:

Be it known that I, GRIFFITH E. WILLIAMS, a citizen of the United States, residing at Cambria, in the county of Columbia and State of Wisconsin, have invented certain new and useful Improvements in Bombs, of which the following is a specification, reference being had to the accompanying drawings.

10 This invention relates to certain improvements in bombs, and has relation more particularly to a device of this general character especially designed to be dropped from an aerial craft, and it is an object of the invention to provide a novel and improved device of this general character from which the projectiles are discharged upon impact with an objective. It is also an object of the invention to provide a device of this 15 general character having novel and improved means whereby projectiles are discharged therefrom in approximately horizontal planes and in radial directions. An additional object of the invention is to provide a novel and improved bomb provided with a plurality of cartridge chambers together with means for exploding the cartridges upon impact of the bomb with an objective.

20 Another object of the invention is to provide a novel and improved bomb of this general character including a bursting charge, together with means whereby the bursting charge is caused to explode after the cartridges have been discharged.

25 It is a further object of the invention to provide a novel and improved bomb of this type wherein a portion thereof is provided with a plurality of cartridge chambers, and 30 wherein a second portion affords a chamber for a bursting charge, together with a member movable upon contact with an objective for first discharging the cartridges and then exploding the bursting charge.

35 The invention also embodies a novel and improved construction which provides a plurality of cartridge chambers and a chamber containing a bursting charge, and wherein means operate upon impact of the bomb 40 with an objective for discharging the cartridges and for closing an electric circuit to explode the bursting charge.

45 The invention consists in the details of

construction and in the combination and arrangement of the several parts of my improved bomb whereby certain important advantages are attained and the device rendered simpler, less expensive and otherwise more convenient and advantageous for use, as will be hereinafter more fully set forth. 55 60

The novel features of my invention will hereinafter be definitely claimed.

In order that my invention may be the better understood, I will now proceed to describe the same with reference to the accompanying drawings, wherein:

Figure 1 is a view partly in elevation and partly in longitudinal section taken through a bomb constructed in accordance with an embodiment of my invention; 70

Fig. 2 is an enlarged fragmentary view partly in elevation and partly in section illustrating the firing mechanism coacting with a cartridge chamber;

Fig. 3 is an enlarged fragmentary view 75 partly in elevation and partly in section illustrating the operative connection between the endwise movable member or rod and the shaft for controlling the explosion of the bursting charge; and 80

Fig. 4 is a diagrammatic view illustrating the igniting system for a bursting charge.

As disclosed in the accompanying drawings, my improved bomb comprises a body B divided longitudinally to afford three 85 chambers or compartments A, B, and C. The chambers A, B, and C are separable, but are maintained in assembled relation by having adjacent end portions in threaded engagement as indicated at 1. The end 90 chambers A and C are each adapted to contain a bursting charge X, and extending outwardly and longitudinally from the outer end of the rear section C are the wings or vanes W, while the forward section A is 95 substantially conical in form with its apex outwardly directed. As is believed to be clearly understood, the wings or vanes W serve to guide the bomb B in its downward flight. 100

The central chamber B is provided with a plurality of openings 2, in each of which is threaded or otherwise secured the discharge end portion of a radially disposed cartridge chamber or barrel 3 extending inwardly of the compartment B. The inner

end of each of the barrels 3 is provided with a removable cap 4 so that a cartridge *c* may be readily inserted therein. The cartridge *c* may be of any type preferred such as solid shot or otherwise as may be deemed the most expedient.

Extending outwardly from each of the caps 4 at substantially its axial center is a tube 5 of predetermined length, and in 10 which is arranged a firing pin 6 adapted to properly engage a cartridge to discharge the same. The pin 6 is provided with a longitudinally disposed slot 7, through which is directed a pin 8 carried by an intersecting bore of the tube 5, whereby the firing pin 6 is capable of limited endwise movement.

Extending longitudinally of the tube 5 at the axial center thereof is an endwise movable rod R which extends outwardly of the body B through the outer end or apex portion of the section A. The rod R is of a length to intersect the compartments A and B, and to extend within the rear compartment C. Pivottally engaged with the rod R within the compartment B is an arm 7^a for each of the tubes 5, and which extends therein and terminates in close proximity to the outer end of the firing pin 6 so that upon 20 the rod R being forced inwardly by impact with an objective the arm 7^a will strike the firing pin 6 with sufficient force to cause the pin 6 to explode the cartridge within the chamber or barrel 3.

As clearly illustrated in the accompanying drawings, the chambers or barrels 3 are arranged in a plurality of series spaced longitudinally along the section B with the chambers or barrels of each series extending 30 entirely around the section A and in radial arrangement.

The rear end portion of the central section B is intersected by the transversely disposed shaft 8^a supported by the inwardly directed 40 bearings 9 carried by diametrically opposed portions of the sections B. The central portion of the shaft 8 is provided with a pinion 10 or the like which meshes with the longitudinally disposed rack 11 carried by the inner end portion of the rod R so that upon 50 endwise movement being imparted to the rod R the shaft will be caused to rotate. Arranged within each of the sections A and B is a spark generating system or mechanism S in communication with an electrical source E of any preferred character, and interposed within one of the conductors *a* is a circuit closer 12 of any preferred type including a removable member. The closer 12 is normally open and the movable member 12' thereof has engaged therewith a flexible member 14 which extends within the section B and is engaged with the shaft 8^a. Normally the flexible member 14 is slack so that upon rotation of the shaft 8 sufficient pull

will not be imposed upon the member 14 to close the circuit closer 12 until after the cartridges *c* have been discharged.

Mounted upon the shaft 8^a is a balance wheel 15 whereby the requisite rotation of the shaft to effect the winding therearound of the flexible members 14 to effect an explosion of the charges within the sections A and B is materially facilitated.

From the foregoing description, it is 75 thought to be obvious that a bomb constructed in accordance with my invention is particularly well adapted for use by reason of the convenience and facility with which it may be assembled and operated, and it 80 will also be obvious that my invention is susceptible of some change and modification without departing from the principles and spirit thereof, and for this reason I do not 85 wish to be understood as limiting myself to the precise arrangement and formation of the several parts herein shown in carrying out my invention in practice except as hereinafter claimed.

I claim:

1. An aerial bomb comprising a body provided with series of substantially radially disposed cartridge chambers, a tube in communication with each of the chambers, a firing pin mounted for movement in said tube, an impact actuated member carried by the body and means coacting with each of the firing pins and operated by the impact actuated member for imparting movement to the firing pin toward the cartridge chamber when the impact actuated member is moved under impact.

2. An aerial bomb comprising a body provided with series of substantially radially disposed cartridge chambers, a tube in communication with each of the chambers, a firing pin mounted for movement in said tube, and an impact actuated rod carried by the body, arms pivotally engaged with said rod, each of said arms extending within a tube for contact with a firing pin when the rod is moved under impact.

3. An aerial bomb comprising a body provided with series of substantially radially disposed cartridge chambers, a tube in communication with each of the chambers, a firing pin mounted for movement in said tube, and an impact actuated rod carried by the body, arms pivotally engaged with said rod, each of said arms extending within a tube for contact with a firing pin when the rod is moved under impact, said tube and firing pin being provided with coacting means for limiting the movement of the firing pin.

4. An aerial bomb comprising a body provided with cartridge chambers and with a chamber to contain a bursting charge, an impact actuated member, means operated by said member for discharging the cartridges

within the cartridge chambers, electrical means carried by the body for igniting the bursting charge, said means including a normally open circuit closer, a rotatable shaft 5 carried by the body, a flexible connection between the shaft and the circuit closer whereby the circuit closer is closed upon rotation of the shaft, and means whereby the shaft

is rotated upon the movement of the impact actuated member.

In testimony whereof I hereunto affix my signature in the presence of two witnesses.

GRIFFITH E. WILLIAMS.

Witnesses:

IRA W. PARKER,

R. G. WILLIAMS.
